UNITED STATES PATENT OFFICE

111,156

DESIGN FOR A TRACTOR

Albert W. Scarratt, Kenilworth, and Theodore H. Koeber, Chicago, Ill., assignors to International Harvester Company, a corporation of New Jersey

Application November 6, 1937, Serial No. 72,669

Term of patent 14 years

To all whom it may concern:

Be it known that we, Albert W. Scarratt and Theodore H. Koeber, citizens of the United States, residing at Kenilworth, in the county of Cook and State of Illinois, and at Chicago, in the county of Cook and State of Illinois, respectively, have invented a new, original, and ornamental Design for a Tractor, of which the following is a specification, reference being had to the accompanying drawings, forming part thereof, in which:

We claim:

The ornamental design for a tractor, as shown.

ALBERT W. SCARRATT.

THEODORE H. KOEGER.
